UNITED STATES PATENT OFFICE.

SCOTT VANNATTA, OF MARCELLUS, MICHIGAN.

OIL-HEATER.

1,140,780.

Specification of Letters Patent. Patented May 25, 1915.

Application filed September 14, 1914. Serial No. 861,709.

To all whom it may concern:

Be it known that I, SCOTT VANNATTA, a citizen of the United States, residing at Marcellus, in the county of Cass and State of Michigan, have invented a new and useful Oil-Heater, of which the following is a specification.

The device forming the subject matter of this application is a heater adapted to be assembled with a stove of any desired construction, the heater preferably using kerosene or crude oil as a fuel.

An object of the present invention is to improve the construction of the flame spreader.

Another object of the present invention is to improve the construction of the burner.

A further object of the invention is to provide a novel coöperation between the flame spreader and the burner.

It is within the scope of the invention to improve generally and to enhance the utility of devices of that type to which the present invention appertains.

With the foregoing and other objects in view which will appear as the description proceeds, the invention resides in the combination and arrangement of parts and, in the details of construction hereinafter described and claimed, it being understood that changes in the precise embodiment of the invention herein disclosed, can be made within the scope of what is claimed, without departing from the spirit of the invention.

In the accompanying drawings:—Figure 1 is a side elevation depicting the invention, parts being broken away; and Fig. 2 is a transverse section on the line 2—2 of Fig. 1.

In the accompanying drawings, the numeral 1 indicates a portion of the wall of a stove, furnace, or the like. Disposed within the stove or furnace is a U-shaped pipe denoted generally by the numeral 2 and comprising an upper arm 5 and a lower arm 3, the lower arm 3 being closed at one end by a cap 4. The upper arm 5 of the pipe 2 protrudes through the wall 1 and is equipped terminally with a valve casing 6 having a seat 7 adapted to coöperate with a needle valve 8 actuated by means of a hand wheel 9 or in any other suitable manner. To the lower end of the valve casing 6 is attached a coupling 10 united with one end of a pipe 11 which may be of any desired length, the pipe 11 being united by means of a coupling 12 with a combined oil and air tank 14 hav-

ing a filling plug 15 and a pressure gage 16. Air pressure within the tank 14 is maintained by means of a pump 17 of any desired construction.

Interposed in the lower arm 3 of the U-shaped pipe 2 is a coupling 18 in the form of a T, and including an upstanding neck 19 supporting a cup 20. A screw plug 21 is threaded into the upper end of the section 19 and is provided with a lateral flange 22 which bears upon the bottom of the cup 20 to hold the latter in position. Through the plug 21 is formed an outlet opening 23. The cup 20 may be equipped with an asbestos lining 24.

Any desired number of burners, constructed as above described, may be mounted in the lower arm 3 of the pipe 2.

Interposed in the upper arm 5 of the pipe 2 and located above each burner is a flame spreader, the same preferably comprising a cone 25 provided with lateral couplings 27 receiving constituent portions of the upper arm 5 of the U-shaped pipe 2. In the cone 25 is formed a V or loop-shaped, depending passage 28, the upper ends of which open into the couplings 27 as will be understood readily from the drawings. In this passage is disposed a filtering material indicated at 29. This material is preferably thoroughly washed gravel, although another filtering material may be employed if desired.

In practical operation, a pressure is created in the oil tank 14 through the action of the pump 17. The oil tank may be located at a considerable distance from the stove, and the danger of explosion, therefore, may be reduced to a minimum. A sufficient pressure may be maintained in the oil tank 14 to cause the oil to traverse the pipe 11 and pass by way of the valve casing 6 into the upper arm 5 of the U-shaped pipe 2. As the oil traverses the upper arm 5, the oil descends into the depending loop-shaped passages 28 of the flame spreaders 25 and the conversion of the oil into gas is accordingly enhanced, owing to the sinuous path which the oil is compelled to travel, it being recalled, of course, that the spreaders 25 are enveloped by flames and are in a highly heated condition. Further, as the oil traverses the depending loop-shaped passages 28, the oil is filtered, owing to the presence of the filtering material 29. Ultimately, the gas emerges through the outlet openings 23

in the burner plugs 21 and is there ignited. The cups 20 are so constructed that each cup may hold a priming charge to be employed initially in heating the cones or flame spreaders 25 at the inception of the operation of the device. The plug 21 exercises a double function in that it serves to hold the cup 20 in place and serves also as a gas supplying nozzle.

Having thus described the invention, what is claimed is:

1. In a device of the class described, a supply pipe including a neck; a cup resting on the neck; and a plug inserted into the neck, the plug having a flange engaging the bottom of the cup to hold the cup on the neck, the upper end of the plug being free and being located below the upper edge of the cup, the plug having an opening defining a combustion mouth within the contour of the cup.
2. In a device of the class described, a delivery pipe comprising upper and lower arms; a burner in the lower arm; and a de-

pending conical flame spreader in the upper arm above the burner, the flame spreader having a depending loop-shaped passage forming a continuation of the bore of the upper arm and of substantially the same cross section as the bore of the arm.

3. In a device of the class described, a delivery pipe comprising upper and lower arms; a burner in the lower arm; a depending conical flame spreader in the upper arm above the burner, said spreader having a depending loop-shaped passage forming a continuation of the bore of the upper arm and of substantially the same cross sectional area as the bore of the arm; and filtering material in the passage.

In testimony that I claim the foregoing as my own, I have hereto affixed my signature in the presence of two witnesses.

SCOTT VANNATTA.
